UNITED STATES PATENT OFFICE.

JOHN H. WYGANT AND RICHARD P. PAULISON, OF HACKENSACK, N. J.

IMPROVEMENT IN BABY-SWINGS.

Specification forming part of Letters Patent No. 127,134, dated May 21, 1872.

Be it known that we, JOHN HENRY WYGANT and RICHARD P. PAULISON, both of Hackensack, in the county of Bergen, in the State of New Jersey, have invented a new and useful Improvement on a Portable Baby Swing and Jumper; and we do hereby declare that the following is a full and exact description thereof, reference being had to the accompanying drawing and the letters of reference marked thereon.

The nature of this invention consists of a combined portable baby swing and jumper, constructed as hereinafter described.

To enable others skilled in the art to make and use our invention, we will proceed to describe it.

Figure 1 is a perspective view.

A A A A is the frame of the machine, substantially constructed of wood to resist the vibration of the operating parts, and connected by hinges to make it folding. B is the oscil-

lating cross-bar, through which the wires C C are passed, and to which the body D is suspended, and also to which the crank E is fastened. F is the treadle attached to the bottom of upright A. G is the wire connecting treadle and crank, by which motion is given to the swing. D is the body, (with a movable seat,) having a hole to admit of a child being placed therein, and connected to wires C C C by helical springs to give perpendicular motion as a jumper.

What we claim is—

The baby swing and jumper, as described and set forth, in combination with the portable folding frame.

JOHN H. WYGANT.

RICHARD P. PAULISON.
